UNITED STATES PATENT OFFICE.

GEOORG LOEBBECKE, OF ZEHLENDORF, NEAR BERLIN, GERMANY.

PROCESS OF MANUFACTURING BAG OR PACKING PAPER.

1,107,807.

Specification of Letters Patent. Patented Aug. 18, 1914.

Application filed May 21, 1907. Serial No. 374,976.

To all whom it may concern:

Be it known that I, GEORG LOEBBECKE, managing director, a subject of the King of Prussia, and resident of Zehlendorf, near Berlin, Kingdom of Prussia, German Empire, have invented a new and useful Process of Manufacturing Bag or Packing Paper, of which the following is a specification.

The present invention relates to a process for the manufacture of craped or goffered paper to be used for packing purposes, *i. e.* paper bags. The novelty is especially seen in the fact that the craped or goffered paper, hereinafter to be called the fashioned paper, is firm in its creases and little capable of yielding and therefore adapted, due to its special character and qualities, for the manufacture of paper bags which are to be used for carrying cement, grains or the like up to 50 kilograms without being liable to tear when being under the strain of such weights and being carried about. This great advantage, *i. e.* the high tensile strength of the paper bags according to the invention, is solely due to the use of paper which has undergone a craping or goffering process, whereby its surface is highly increased per surface unity and consequently the pressure per surface unity greatly decreased relatively.

When carrying out the invention, the dry moist or wet paper, consisting of a paper pulp tough or ground corresponding to the character of the fibers, is craped or goffered during its formation in a paper machine by means of scrapers, goffering rollers or any suitable means and then is submitted to the drying process. At the same time the crapage or gofferage imparted to the paper is maintained in such a manner that during the drying process the fashioned paper is neither able to increase nor shrink longitudinally, whereby the increased surface of the paper due to craping or goffering the same is maintained.

In carrying out the drying process, the fashioned, *i. e.* the craped or goffered paper may be temporarily submitted to pressure, for instance to pressure rollers in such a manner that the crumpled pleats or creases in the paper produced by craping or goffering the same, are pressed together. Thus the over great extensibility or elasticity of the fashioned paper is reduced, whereas the tensile strength and tenacity is increased by a felting process which thus takes place. At

the same time the pressing assists to completely dry the paper and smooth the same in such a manner that it can be printed upon and the pliable leather-like character or quality of the same produced by craping or goffering the paper is increased. A greater pliability can even further be obtained by drying the fashioned wet or moist paper between endless sieves or the like running together with the same which press their surfaces into the paper and thus maintain the crapage or goffered imparted to the paper and at the same time produce a second more delicate gofferage of the same.

A machine for carrying into effect the present invention is represented in the accompanying drawing, the separate figures of which are to be considered as connected one with another at the lines A—A of Figures 1 and 2, B—B of Figs. 2 and 3 and C—C of Figs. 3 and 4. All figures show in combination a machine for the production of craped or goffered paper according to the present invention, including a paper machine, a craping or goffering device, an endless felt for transporting the craped or goffered paper, a drying and pressing apparatus and a rolling up apparatus for rolling up the craped or goffered and dried paper. The machine is shown in side elevation.

Fig. 1 shows the main part of a paper machine *a* of the ordinary construction. The paper-pulp contained in the tank *b* flows down to the metal sieve *c* running over a series of metal rolls *d* in the usual manner. The paper web formed is passed over sucking apparatuses *e* and afterward between the rolls *f* of a couching apparatus as shown in Fig. 2. The couched paper is afterward passed around a roll *g* of a second couching apparatus. A scraper *h* arranged near the upper surface of such roll *g* is used for craping or goffering the paper formed which after such craping or goffering operation, causing the production of creases, is fed by means of an endless felt *j* to the drying cylinders *i*, *k* arranged in series one above another in such a manner that one drying cylinder *k* of the upper series is situated between two adjacent drying cylinders *i* of the lower series as shown in Figs. 3 and 4.

The speed of the endless felt *j* causing the feeding of the paper to the drying cylinders is regulated in such a manner that the creases of the craped or goffered paper are

prevented against extension and maintained substantially during the feeding of the paper away from the scraper *h* and the roll *g*. Around the lower surface of each drying cylinder *i* an endless felt *l* and around the upper surface of each drying cylinder *k* a felt *m* is passed in such a manner that the craped or goffered web to be dried is first moved along between the lower surface of each lower drying cylinder *i* and its felt *l* and afterward moved along between the upper surface of each drying cylinder *k* and its felt *m*. During this continued passage around the cylinders *i* and *k*, the craped or goffered paper is dried accordingly.

The speed of the rotating drying cylinders *i* and *k* is so regulated that during the passage of the craped or goffered paper through the drying apparatus the creases formed in the paper are not extended and that the craping or gofferage imparted to the wet paper as well as the increased surface of the latter due to craping or goffering are maintained. Now to press together the creases of the paper during its drying operation, the upper surfaces of some of the upper felts *m* are in contact with pressing rolls *n* and likewise the lower surfaces of the lower felts *l* are in contact with pressing rolls *o*. These rolls *n* and *o* are supported between the forked ends of the weighted levers *p* and *q* in such a manner that they may exert a suitable pressure against the surface of the felts *l* *m*, to compress the creases formed by craping or goffering the paper. The pressure of such pressing rolls may increase gradually and in ratio to their distance from the first drying cylinders *i*, *k*. To obtain a supplemental gofferage of the nearly fully dried, craped or goffered paper web, the last two, three or four drying cylinders *i* and *k* may be provided with endless metal bands or sieves *t* and *u* replacing the felts running in an end-
less manner around such cylinders. These metal bands or sieves are pressed into the paper web being still in a moist state by the rolls *o* and *n* acting now by pressure, whereby the supplemental gofferage of the paper produced is secured. From the last cylinder *i* of the lower series, the craped or goffered, dried and pressed paper is passed between another set of pressing rolls *r* and *s*

and around a drying cylinder *t* by means of an endless metal band *u*. This supplementary 55 pressing and drying action against the craped or goffered paper may be repeated by a cylinder *v* partially surrounded by an endless band *w*, so that a thoroughly craped or goffered dried and pressed paper may 60 leave the apparatus described. The creases of the resulting product are maintained by the pressure exerted to them several times and the paper so prepared may be rolled up separately on one of a series of rolls *z* which 65 may be withdrawn if necessary separately from their supports and delivered to places where the product may be worked further on.

The pressure exerted to the craped or goffered paper during drying renders the latter 70 firm and reduces its elasticity.

What I claim is:—

1. The process of manufacturing bag or packing paper, consisting in first craping or goffering the paper during its formation on the paper machine while in a moist condition, restraining the craped or goffered paper against elongation between traveling surfaces and exposing the craped or goffered paper, during the drying operation, to pressure for compressing the crapes or gofferings and producing an additional felting thereof.

2. The process of manufacturing bag or packing paper, consisting in first craping or goffering the paper during its formation on the paper machine while in a moist condition and subsequently, while still in a moist condition, guiding and restraining the craped or goffered paper against elongation between traveling surfaces, thereby maintaining the crapes or gofferings and exposing the craped or goffered paper while under restraint between the traveling surfaces to pressure for compressing the crapes or gofferings and producing an additional felting thereof.

In testimony, that I claim the foregoing as my invention, I have signed my name in 100 presence of two witnesses, this 7th day of May 1907.

GEORG LOEBBECKE.
